Primary Examiner — Daniel J Domino(74) *Attorney, Agent, or Firm* — Alberto Q. Amatong, Jr.; Amatong McCoy LLC**CLAIM**

The ornamental design for a display screen or portion thereof with graphical user interface, substantially as shown and described.

DESCRIPTION

The FIGURE is a front view of a display screen or portion thereof with graphical user interface.

The broken lines showing a display screen or portion thereof and elements of the graphical user interface illustrate portions of the article, and form no part of the claimed design.
